[57] CLAIM

The ornamental design for a belt buckle having a hidden currency compartment, as shown and described.

DESCRIPTION

FIG. 1 is a perspective view from the front of the belt buckle showing our new design;

FIG. 2 is a side elevational view as taken from the rear of FIG. 1;

FIG. 3 is an end elevational view as taken from the left hand end of FIG. 2;

FIG. 4 is an end elevational view as taken from the right hand end of FIG. 2;

FIG. 5 is a rear elevational view thereof; and

FIG. 6 is a perspective view thereof in the open position.
